UNITED STATES PATENT OFFICE.

EDWIN J. HEARST, OF ASHBORO, NORTH CAROLINA.

GAME-COUNTER.

1,196,358.

Specification of Letters Patent.

Patented Aug. 29, 1916.

Application filed May 17, 1915. Serial No. 28,696.

To all whom it may concern:

Be it known that I, EDWIN J. HEARST, a citizen of the United States, residing at Ashboro, in the county of Randolph, State 5 of North Carolina, have invented certain new and useful Improvements in Game-Counters; and I do hereby declare the following to be a full, clear, and exact description of the invention, such as will enable 10 others skilled in the art to which it app pertains to make and use the same.

This invention relates to new and useful improvements in markers or counters for keeping score of a game, and is particularly 15 directed to the provision of such a device which is of a multiple character.

The object of the present invention resides in the provision of a counter to be used for keeping the score of games such as 20 "rook", in which a high score is made and which is also adapted with auxiliary means for keeping the score of games such as "seven-up" or "set-back", it being more particularly the object to provide a novel arrangement of parts for indicating the minus 25 score when a player is in the "hole".

With the above and other objects and advantages in view, the invention resides more particularly in the combination, formation 30 and arrangement of parts hereinafter described and specifically pointed out in the appended claim.

Reference is had to the accompanying drawing wherein similar characters of reference 35 designate corresponding parts throughout the several views, and in which:

Figure 1 is a plan view of the improved counter, Fig. 2 is a central vertical sectional view taken therethrough on the line 2—2 40 of Fig. 1; Fig. 3 is a plan view of the central portion of the device, and showing the pivotal mounting of the auxiliary marking devices, and Fig. 4 is a perspective view of one of the long pointers of the device.

Referring now more particularly to the accompanying drawing, the improved counter is shown as comprising a plate 5 on which is positioned a circular series of symbols 6 which are adapted for recording the 45 scores against such as "rook" or other games which involve a relatively high score, these symbols preferably running from "zero" to "220". A plurality of pointers 7 are provided for indicating the scores in conjunction 50 with these symbols and this pointer is

so mounted that it does not interfere with the operation of auxiliary scoring devices to be hereinafter described, this pointer being also adapted for indicating a plus or minus score with the same symbols. 60

The pointers are preferably of different colors to designate different players. To pivotally mount these pointers at the center of the series of symbols 6, a pivot pin 8 is passed through the plate and through 65 pivot openings in the inner ends of the pointers, suitable washers 9 being disposed between the pivoted ends of the pointers so that when one pointer is moved, the adjacent ones will not be moved thereby. 70 Flanges 10 are provided at the side portions of each pointer 7 and have their edges bent to form guide grooves slidably holding a plate 11 which is adapted to slide on the face of the pointer and cover or uncover a 75 suitable symbol thereon, such as the word "Set" so that when the player is set back, he may slide the plate to expose this symbol and the number indicated by the pointer will indicate his minus score. 80

Auxiliary counting devices for indicating the number of games won by each player or for indicating the scores of games, such as "seven-up" or "set-back", which comprises 85 a plurality of series 12 of symbols, the symbols of each series being arranged substantially in a quadrant. Pointers 13 are provided in conjunction with the series of symbols 12 and each of these pointers is pivoted on a pin 14 engaged in the plate adjacent 90 the central pivot pin 8 so each pointer will swing radially with respect to a respective series of symbols. The pins 14 have their inner ends secured in a disk 15 mounted on the pin 8 whereby a strong structure is provided. To provide means whereby the mounting of these auxiliary pointers will not interfere with actuations of the main pointers, a second disk 16 is secured on the pivot pin 8 between the innermost pointer 7 100 and the pointers 13 and lies over the disk 15 and the pivoted ends of these pointers. To provide a means for limiting the pivotal movements of the pointers 13, a hub member 19 is secured on the pin 8 and is provided 105 with radial arms 20 extending between the indicator members 13. The indicator members 13 may be colored variously as may the indicators 7 so that they may be readily identified by the player using the indicators 110

7, each of whom it will be understood selects a certain counter whereby the score is kept.

From the foregoing it is observed that 5 an exceedingly simple counting device has been provided whereby the scores of a plurality of games may be readily and accurately kept, the pivotal connection of the various counters or indicators being sufficiently tight to prevent undesired movements thereof.

What is claimed is:

In a counter of the class described, the combination with a plate and a circular

series of symbols thereon, of a plurality of 15 pointers pivoted at a common center on the plate to swing radially with respect to said series of symbols, a symbol on each of the pointers and a plate slidably mounted on each of the corners to cover or uncover the 20 said symbol.

In testimony whereof, I affix my signature in the presence of two witnesses.

EDWIN J. HEARST.
